OPEN HOLE HOOK WALL PACKER

Joseph D. Smith, Shreveport, La., and William B. Taylor, Houston, Tex., assignors to Johnston Testers, Inc., Houston, Tex., a corporation of Delaware

Application June 6, 1952, Serial No. 292,068

4 Claims. (Cl. 166—138)

This invention relates to an open-hole packer. A main object of the present invention is to provide an improved open hole hook wall packer.

A more particular object of the present invention is to provide such a packer wherein there is provided an expandable packer sleeve arranged to be expanded outwardly into engagement with the walls of a well bore upon telescopic movement of parts of the packer, said packer having well bore walls engaging dogs normally retained against outward movement, but adapted to be cammed outwardly into engagement with the walls of the well bore by proper manipulation of the packer to hold one of the telescopic parts stationary, to enable telescopic movement of said parts and therefore cause expansion of the packer sleeve.

A further object of the present invention is to provide a packer as above described which can be easily set in an open hole and then collapse and then readily re-set in another location.

Various other objects of the present invention will be apparent from the following description taken in conjunction with the accompanying drawings wherein:

Figs. 1a and 1b disclose in elevation a packer embodying the concepts of the present invention, showing the upper portion of the packer in mid-section, the parts being depicted in running-in condition.

Figs. 2a and 2b are views similar to Figs. 1a and 1b, respectively, but showing the packer after the dogs have been hooked into the walls of the well bore.

Figs. 3a and 3b are views similar to Figs. 1a and 1b, respectively, but showing the subsequent stage of operation where the expandable sleeve has been expanded into engagement with the walls of the well bore to sealingly engage the same.

Figs. 4 and 5 are fragmentary views showing how the cam edge on the spring sleeve functions to rotate the sleeve during unsetting of the packer.

Referring to the accompanying drawings wherein similar reference characters designate similar parts throughout, the packer there disclosed comprises an upper composite tubular mandrel 11 threadedly connected at its upper end to the lower end of a drill string 13, and slidably receiving within its lower portion the upper end of a lower composite tubular mandrel 15. Threadedly connected to the lower end of lower mandrel 15 is an oil well tool generally entitled 16 of any desired type, such as, for instance, a formation fluid tester. The packer functions to sealingly engage the walls of a well bore and separate the fluid above the packer from the fluid and operations taking place below the packer, or conversely separating the fluid below the packer from the fluid and operations taking place above the packer.

The upper end of lower mandrel 15 is keyed to mandrel 11 by keys 17, and carries a nut 19 which normally rests on a shoulder 21 provided on upper mandrel 11 when the packer is being run into or out of a well. Also formed on mandrel 11 is a shoulder 23 for limiting upward movement of lower mandrel 15 relative to the upper mandrel.

Suspended from upper mandrel 11 by a flanged split ring 25 is a resilient packer sleeve 27, which is connected to said split ring 25 by a perforated band 29, the latter being partially embedded in the upper end of the sleeve as is apparent from the drawings. Band 29 and split ring 25 are connected together by inter-engaging flanges formed on the band and ring as disclosed in the drawings, and said split ring and upper mandrel 11

2

are likewise connected by inter-engaging flanges formed on the ring and upper mandrel. Sleeve 27 is connected at its lower end to lower mandrel 15 by a similar band 31 and a similar split ring 33. Split rings 25 and 33 are held together by bolts 25a and 33a respectively.

By the above construction, the packer sleeve 27 is positively connected to the lower and upper mandrels to enable positive control over its movements.

It is apparent that when lower mandrel 15 is held stationary in the well, in a manner to be presently explained, sleeve 27 may be expanded into engagement with the walls of the well bore by a downward movement of drill string 13, which causes a consequent downward sliding movement of upper mandrel 11 along lower mandrel 15 to expand said sleeve.

For hooking lower mandrel 15 to the walls of the well bore, said mandrel is provided with an enlarged portion 34 having pivotally mounted thereon a plurality of dogs 35 by means of pivot pins 37, said dogs being mounted for outward swinging movement into engagement with the walls of the well bore, but normally being constrained to assume inward positions by leaf or strip springs 39 secured to enlarged portion 34 and engaging said dogs.

In their inward positions, dogs 35 bear against the upper tapered end of a spring sleeve 41, which is slidably mounted on the lower reduced end 38 of lower mandrel 15. Sleeve 41 carries a plurality of bowed springs 43 adapted for frictional engagement with the walls of the well bore.

Formed in sleeve 41 is an inverted J slot 45 accommodating a screw 47 which is threaded into lower mandrel 15. J slot 45 is in part defined by an inclined cam edge 49 adapted to be engaged by screw 47 when the screw is moved upwardly along the long side of slot 47, upon an upward movement of lower mandrel 15 relative to sleeve 41, to turn sleeve 41 and dispose the screw in the shorter side of the J slot to condition the packer for further downward or upward movement in the well.

In operation the packer is lowered into the well in the condition shown in Figs. 1a and 1b until the packer is located approximately at the zone which it is desired to set the same. The drill string is then slightly raised to lift screw 47 upwardly a slight amount and the drill string turned in a direction to dispose the screw in the long side of the J slot while the sleeve 41 is held against movement by frictional members 43 engaging the bore wall. Thereafter, upon subsequent lowering movement of the drill string, springs 43, being in frictional engagement with the walls of the well bore, will prevent downward movement of sleeve 41 so that the dogs 35 are cammed outwardly by the upper tapered end 40 of relatively stationary sleeve 41 into hooking engagement with the walls of the well bore. This stage of operation is disclosed in Figs. 2a and 2b where it will be noted that sleeve 27 is only slightly expanded at this time.

When the dogs take hold, lower mandrel 15 is held stationary so that upon further downward movement of the drill string, upper mandrel 11 moves downwardly relative to the now stationary lower mandrel 15 to compress sleeve 27 and cause outward expansion thereof into sealing engagement with the well bore walls. Shoulder 23 serves to limit downward movement of upper mandrel 11 relative to lower mandrel 15 to prevent damage to the packer by undue compression thereof.

The particular operations or tests to be performed are now commenced. After completion of such tests, when it is desired to collapse the packer, an upward pull on the upper mandrel 11 serves to collapse sleeve 27, and when nut 19 engages shoulder 21, lower mandrel 15 is lifted to lift the dogs 35 out of hooking engagement with the walls of the well bore and away from (but not out of contact with) the tapered end of sleeve 41 to allow the dogs to assume inoperative positions under the influence of springs 37. During upward movement of lower mandrel 15 relative to sleeve 41, screw 47 comes into engagement with cam edge 49 as shown in Fig. 4 so that the sleeve is rotatably cammed around to dispose the screw into the short side of the J slot as shown in Fig. 5. Thereafter, the drill string may be lowered or raised to dispose the packer at a new location, at which

the packer can be set again by a repetition of the operation above described.

By the present invention, an improved open hole hook wall packer has been provided which can be readily set in a well bore to seal off the zone above the packer from the zone below the packer, and thereafter readily collapse and reset when and where desired.

While we have shown the preferred form of our invention, it is to be understood that various changes can be made in its construction by those skilled in the art without departing from the spirit of the invention as defined in the appended claims.

Having thus described our invention, what we claim and desire to secure by Letters Patent is:

1. A device of the class described, comprising telescopically arranged upper and lower mandrels adapted to be suspended from a string of drill pipe and carrying an expandable packer sleeve arranged to be expanded upon contracting telescopic movement of the mandrels, well bore wall penetrating means on the lower mandrel for holding said lower mandrel stationary to permit contracting telescopic movement of the mandrels comprising pointed dogs pivoted at their upper ends to said lower mandrel, spring means fastened to said lower mandrel and engaging said dogs for retaining said dogs in an ineffective position, and means for moving said penetrating means to an effective position against the resistance of the restraining means, said last-mentioned means comprising a cam sleeve slidably mounted on said lower mandrel and means on said sleeve for frictionally engaging the bore wall.

2. A device of the class described, comprising an upper mandrel having means for connection to a string of drill pipe and telescopically receiving the upper end of a lower mandrel, an expandable packer sleeve secured at its ends to the upper and lower mandrels and adapted to be expanded upon contracting telescopic movement of the mandrels, well bore wall penetrating means on the lower mandrel for holding said lower mandrel stationary to permit contracting telescopic movement of the mandrels comprising pointed dogs pivoted at their upper ends to said lower mandrel, spring means fastened to said lower mandrel and engaging said dogs for retaining said dogs in an ineffective position, and means for moving said penetrating means to an effective position against the resistance of the restraining means, said last-mentioned means comprising a cam sleeve slidably mounted on said lower mandrel and means on said sleeve for frictionally engaging the bore wall.

3. A device of the class described, comprising an upper mandrel having means on the upper end thereof for connection to a string of drill pipe and telescopically receiving the upper end of a lower mandrel, an expandable packer sleeve secured at its opposite ends to the upper and lower mandrels and adapted to be expanded upon

contracting telescopic movement of the mandrels, a plurality of pointed dogs swingingly mounted on the lower mandrel, a sleeve slidably mounted on said lower mandrel below said dogs having means for frictional engagement with the walls of a well bore and having a camming portion at its upper end for camming the dogs outwardly into engagement with the walls of the well bore, said sleeve having formed therein an inverted J slot, and a pin on the lower mandrel disposed in said slot in the shorter leg thereof to restrain said sleeve against movement camming said dogs outwardly into engagement with the walls of the well bore, whereby when said tool is turned relative to said sleeve said pin is moved into the longer leg of said J slot and then may be moved downwardly relative to said sleeve to cam said dogs outwardly into engagement with the walls of the well bore.

4. A device of the class described, comprising an upper mandrel having means on the upper end thereof for connection to a string of drill pipe and telescopically receiving the upper end of a lower mandrel, an expandable packer sleeve secured at its opposite ends to the upper and lower mandrels and adapted to be expanded upon contracting telescopic movement of the mandrels, a plurality of pointed dogs swingingly mounted on the lower mandrel, a sleeve slidably mounted on said lower mandrel below said dogs having means for frictional engagement with the walls of a well bore and having a camming portion at its upper end for camming the dogs outwardly into engagement with the walls of the well bore, said sleeve having formed therein an inverted J slot, a pin on the lower mandrel disposed in said slot in the shorter leg thereof to restrain said sleeve against movement camming said dogs outwardly into engagement with the walls of the well bore, whereby when said tool is turned relative to said sleeve said pin is moved into the longer leg of said J slot and then may be moved downwardly relative to said sleeve to cam said dogs outwardly into engagement with the walls of the well bore, and a cam defining part of the J slot engageable with said pin when the pin is moved upwardly within the long side of the J slot to cam said sleeve around to dispose the pin within the short side of said J slot.
